UNITED STATES PATENT OFFICE.

KARL NACKE, OF BROOKLYN, NEW YORK, ASSIGNOR TO UNITED METAL SPINNING COMPANY, INC., OF BROOKLYN, NEW YORK, A CORPORATION OF NEW YORK.

DESIGN FOR A PLATE FOR LIGHTING FIXTURES.

Application filed August 12, 1922. Serial No. 3,358. Term of patent $3\frac{1}{2}$ years.

To all whom it may concern:

Be it known that I, KARL NACKE, a citizen of the United States, and resident of Brooklyn, in the county of Kings and State of New York, have invented a new, original, and ornamental Design for Plate for Lighting Fixtures, of which the following is a specification, reference being had to the accompanying drawing, forming part thereof.

Fig. 1 is a front view of a plate for lighting fixtures, showing my new design;

Figs. 2 and 3 are outline views of my plate, and are given to show the contour of the surface ornamentation.

I claim—

The ornamental design for a plate for lighting fixtures, as shown.

KARL NACKE.
